ATTORNEY

UNITED STATES PATENT OFFICE.

PAUL E. BRENEMAN, OF DETROIT, MICHIGAN, ASSIGNEE TO THE STUDEBAKER CORPORATION, OF SOUTH BEND, INDIANA, A CORPORATION OF NEW JERSEY.

TOP CONSTRUCTION.

Application filed March 17, 1926. Serial No. 95,316.

This invention relates to vehicle bodies having tops of the permanent type, and more particularly to improvements in side rail constructions therefor, the principal object being to provide a side rail of new and improved design, which will be lighter in weight, more simple in construction and more economical to manufacture than top side rails used heretofore.

10 Another object is to provide a permanent type top with a side rail, the main portion of which is of sheet steel metal.

15 A further object is to provide a top of the permanent type with a substantially hollow side rail formed from a continuous sheet of metal, to the free ends of which a wooden tacking strip is secured.

20 These, being among the objects of the present invention, the same consists of certain features of construction and combinations of parts to be hereinafter described with reference to the accompanying drawing, and then claimed, having the above and other objects in view.

25 In the accompanying drawing which illustrates a suitable embodiment of the present invention, and in which like numerals refer to like parts throughout the several views:

30 Figure 1 is a perspective view of a fragment of a vehicle body provided with a top of the permanent type incorporating an embodiment of the present invention therein.

Figure 2 is a perspective sectional view taken transversely through a side rail just 35 adjacent one of the cross bows.

Figure 3 is a sectional view taken transversely through the side rail of Figure 2 and longitudinally through a cross bow.

40 Figure 4 is a fragmentary perspective view of the lower portion of a side rail, showing one of the stiffening members secured in position thereon.

Figure 5 is a perspective view of one of the brackets used to secure the ends of the 45 cross bows to the top side rails.

The top shown is built up to provide a somewhat similar structure to conventional tops of the permanent type and embodies a 50 pair of roof rails or top side rails 10, as they will be called in the following description, a plurality of cross bows 11 spanning the side rails 10, a front end member 12 and a rear end member 13. These several elements are first assembled to complete the top structure 55 and are then assembled to the vehicle body

as a unit, the side rails 10 providing the main support therefor, suitable brackets and fastening means (not shown) being used to secure the same to the body pillars 14 and body rear panel 15.

60 Referring now to Figures 2 and 3, it is noted that the side rail 10 which constitutes the present invention comprises for the most part a hollow one piece member formed to shape from a continuous strip of sheet metal, 65 the lower portion of which will be designated as a base portion and the upper portion 39 as the shaping portion. It may be formed in two simple operations, the first of which stamps the metal to the necessary shape with the shaping portion 39 extending outwardly from the base portion, and the second of which bends the shaping portion into position. The base portion, after stamping has a form corresponding to a series of steps, 70 comprising a lower horizontal portion 16, a lower riser 17, an upper horizontal portion 18 and an upper riser 19 terminating in an inwardly turned marginal flange 20, and the shaping portion 39 after stamping, as previously stated, extends outwardly from the 75 base portion and is provided with a rounded surface.

80 Before the second operation is performed, a number of spaced stiffening members 21 are secured to the base portion. These stiffening members 21 are preferably shaped from sheet metal as shown in Figure 4, and are formed to such a shape as to provide horizontal attaching faces which are secured to the horizontal portion 16 and the horizontal portion 18, thereby preventing undue flexing of the lower riser 17 which might be caused by weaving of the top. A wooden tacking strip 22 is secured to the upper horizontal portion 18 and riser 19, substantially 85 flush with the flange 20 by nails or screws such as 23, notches as at 24 being cut out to allow the same to fit around the stiffeners 21. Secured by nails or screws such as 25 to the lower riser 17 and lying on the horizontal portion 16 substantially flush with the upper horizontal portion 18, is a brace member 26 90 of wood or the like, notched as at 27 to allow the same to fit around the stiffeners 21.

95 The second operation, that of bending to the final shape, may be performed at this state of assembly, and consists in bending the shaping portion 39 of the side rail 10 upwardly around the outer edge 28 of the brace 100 105 110

member 26 and inwardly, the marginal edge 29 being secured by suitable screws or nails 30 to the upper face of the wooden tacking strip 22. The outer surface of the shaping portion 39, being cored or rounded to complete the shaping of the entire top, lends additional stiffness to the structure and conceals the tacking strip 22 and stiffeners 21.

As previously stated, regularly spaced 10 cross bows 11 bridge the space between the side rails 10 and hold the latter in spaced relation. These cross bows may be of wood or any other material, but in the present construction sheet metal stampings, trough 15 shaped in form, are used as they are better adapted to be secured to the metallic side rails 10. The free edges of these trough shaped cross bows 11 are turned outwardly to provide marginal flanges 31. Welded or 20 otherwise secured to the end of each cross bow 11 is a sheet metal T-shaped stamping 32, such as shown in Figure 5, so positioned that when the cross bow 11 is secured to the under surface of the flange 20, the flanges 25 or wings 33 thereof may be welded or otherwise secured to the upper riser 19 of the side rail base portion, which construction provides a very rigid efficient connection between the cross bows 11 and side rails 10.

30 Suitable top material 34 is provided to cover the top and is fastened to the longitudinal tacking strips 22, a molding such as 35 also being secured thereto to conceal the edges of the top material 34. Suitable head 35 lining 36 may be secured to the inside of the top structure to provide a neat inside appearance. A drip moulding such as 38, if desired, may be secured to the outer edge of each side rail 10 to catch the water that may 40 run off the top in rainy weather.

From the foregoing description it is quite evident that a top side rail constructed after the manner of the present invention has certain advantages over types used heretofore, that it may be easily assembled and is economical to manufacture.

Formal changes may be made in the specific embodiment of the invention described, without departing from the spirit or substance of the broad invention, the scope of

which is commensurate with the appended claims.

What I claim is:

1. A side rail for a vehicle top comprising a single sheet of metal formed to provide a hollow structure having upper and lower portions, the inner edge of said lower portion being formed to provide a vertical and a horizontal abutment, and tacking strips received against said abutments, one of said tacking strips being positioned to receive the free end of the upper portion of said sheet. 55

2. A side rail for a vehicle top comprising a single sheet of metal formed to provide a hollow structure having upper and lower portions, the inner edge of said lower portion having a vertical and a horizontal abutment, and a tacking strip received against said abutments, the marginal edge of said upper portion being secured to the upper face of said tacking strip. 60

3. A side rail for a vehicle top formed from a single sheet of metal to provide parallel offset horizontal faces joined by a vertical wall, the metal extending upwardly and inwardly from the outer edge of the outer horizontal face to a point above the inner edge of the inner horizontal face, a spacing member interposed between and secured to the margins of said sheet, and a brace member secured against said outer horizontal face between said wall and the outer edge of said upwardly and inwardly extending portion. 75

4. A side rail for a vehicle comprising a single sheet of metal formed to provide a hollow structure having upper and lower surfaces spaced at their inner edges, said lower surface being formed to provide a vertical and a horizontal abutment and the upper surface being curved to provide a finished surface for said top, and a tacking strip secured to said vertical and horizontal abutment on said lower surface and to the free edge of said upper surface. 80 85

Signed by me at Detroit, Michigan, U. S. A., this 12th day of March, 1926.

PAUL E. BRENEMAN.
